UNITED STATES PATENT OFFICE.

JOSEPH H. ADAMS, OF BROOKLYN, NEW YORK.

PROCESS OF CONVERTING HYDROCARBON OILS.

Original application filed December 5, 1917, Serial No. 205,527. Divided and this application filed October 12, 1922, Serial No. 593,953.

To all whom it may concern:

Be it known that I, JOSEPH H. ADAMS, a citizen of the United States of America, and a resident of Brooklyn, county of Kings, 5 and State of New York, have invented certain new and useful Improvements in Processes of Converting Hydrocarbon Oils, of which the following is a specification, reference being had to the accompanying drawings, forming a part thereof.

My invention relates to a process of cracking oil and particularly to a thermal and vapor pressure method of converting more or less refined mineral hydrocarbon oils, such 15 as gas oil into more volatile products, such as gasoline.

The apparatus illustrated and hereinafter described, as adapted for use in carrying out the present process, was invented by me 20 but is not herein claimed since it is a part of the subject matter claimed in my Patent No. 1,320,354 granted Oct. 28th, 1919 on an application filed Dec. 1st, 1909.

The present application is a continuation 25 in part of the aforesaid patent, since it is a division of my copending application 205,527, as it was originally filed on December 5, 1917, and which itself was a continuation in part of the aforesaid patent at the 30 time of its filing but which during its prosecution became a true division of the aforesaid patent and matured as such into Patent 1,433,519 on October 24, 1922.

One object of my invention is to provide 35 a cracking process for the purpose above indicated whereby the oil or mixture of oils is subjected to the powerful influence of an internally applied decomposing temperature, while holding the oil and its vapors 40 under super-atmospheric pressure.

Another object of my invention is to provide a process which shall combine the advantages from the use of pressure, and avoid the disadvantages incident to the application 45 of heat to the exterior walls of the cracking chamber in which oil under pressure is contained, thus obviating the baking or hardening of the carbon on the interior walls of the cracking chamber and avoiding 50 great loss of heat resulting from the incrustations on the interior surface, and the great danger of burning and weakening the walls which are subjected to tremendous strain by 55 reason of the pressure within.

Accordingly this invention contemplates 55 cracking oil under super-atmospheric pressure which may be self-imposed by the generation of vapors during the cracking operation, through the direct application of cracking temperatures to the body of oil under 60 treatment through the agency of a suitable internal heating device, that is immersed within the oil and in direct contact therewith, whereby the cracking heat is effectively and locally applied to the oil. Preferably, the heating device takes the form of an electric resistor of carbon, or other suitable heat enduring material, which is submerged in a body of oil that is advantageously retained within a receptacle of re- 65 stricted cross-section so that the oil therein, or passing therethrough, is necessarily in intimate contact with the heater. The heavier constituents of the evolved vapors are separated by condensation from those 70 of desired lighter volatility and are returned or back-trapped to the cracking zone so that they are again subjected to cracking heat, whereby further conversion thereof takes place. The vapors of desired volatility are 75 passed on and subsequently condensed and collected. Substantially the same super-atmospheric pressure self-imposed by the generated vapors is maintained throughout the separation, and cyclic back-trapping, as 80 well as the condensation and collection of the final distillate.

Other objects of the invention and features by means of which they are attained will become apparent from the following 90 description of the process as exemplified in the accompanying drawings.

Referring to the drawings:

Figure 1 is an elevation of a cracking apparatus adapted for practicing the process 95 of my invention.

Figure 2 is a sectional elevation of a converter which constitutes one of the elements of the apparatus of Figure 1.

Figure 3 is a sectional plan view, taken 100 on the line III—III of Figure 2.

Figure 4 is a view corresponding to Figure 1 of a modified apparatus which is also suitable for carrying out the process of my invention.

Figure 5 is a view corresponding to Figure 2 of another modified form of converter that may be employed.

Figures 6 and 7 are respectively an elevation and a plan view of the electric heater utilized in the converters of Figures 2, 4, and 5, drawn to a larger scale.

5 Figure 8 is a sectional plan view taken on the line VIII—VIII of Figure 6, and

Figure 9 is a partially sectional elevation of the heater of Figure 6.

In Figure 1 the containing vessel 1, of the supply apparatus A may be somewhat elevated with respect to the adjacent converter C, so that the gravitating tendency of the oil may augment its flow into the converter under the influence of the compressed air maintained over the surface of oil contained within the tank 1, to cause its delivery into the system against a super-atmospheric vapor pressure maintained over the surface of oil and in the vapors while undergoing conversion and condensation in the converter and condenser.

A suitable frame 2 of wood or metal may be utilized as a support for the tank.

The fluid oil may be admitted into the containing vessel or tank 1, by means of one or more suitable supply pipes indicated by 3, and controlled by valve 4, and when admitting oil the displaced air may escape through pipe 5, controlled by valve 6. This tank is provided with glass sight gages 7, so that the oil level therein may be constantly under observation.

33 A pipe 9 connects the supply tank and converter C, in any desired manner and in order to control the delivery of oil into the converter the valve 10 is provided in the pipe line 9 for this purpose.

As a means of drawing off oil from the tank, the pipe 11 controlled by valve 12, is provided below the pipe fitting under the tank, and in order to supply compressed air to tank 1, pipe 8, leading out from a T fitting in pipe 3, and controlled by valve 8', leads to a compressor or suitable supply of compressed air, so that compression may be employed over the surface of oil in tank 1, to cause its delivery into the converter against a super-atmospheric vapor pressure maintained therein.

50 The converters C proposed for use in this invention may assume diverse forms, certain of which are shown in the drawings, without undergoing an essential difference in character or departing from the spirit of the invention.

The converter shown in Figures 1, 2 and 3 comprises a retort or heating section 13, provided with a glass sight gage 14, and surrounded by a cylindrical crown or dome 15, also provided with a glass sight gage 16.

60 Preferably, but not necessarily, the supply pipe 9 in this form connecting from the supply tank 1, will lead into the upper part of the retort or section 13, which section forms the lower part of the converter C.

This lower section is provided with a pipe 17, controlled by a valve 18, so that when occasion demands, the retort may be emptied and cleaned of any heavy oil or sediment which may have accumulated therein, and 70 the heavy residual oil may be withdrawn from time to time during the operation of the system.

The crown cylinder 15, is secured to the retort 13, by means of suitable interposed flange members 20, which are screw threaded onto the respective parts and are bolted to each other.

Inasmuch as the vapors rising into and filling the crown or dome 15 exert high pressures, I have arranged a cap 21, in close fitting relation with the upper end of the cylinder crown or dome and have utilized as a means for securely retaining the cap in position a number of strong steel bolts which hold this cap securely to the top of the dome. The lower section or retort may be connected with the overlying dome by means of a gage column 22, on which glass sight gages 23 are arranged so that the condition and disposition of the contents of the converter C, may always be the more readily apparent and be susceptible of an intelligent variation.

90 A feature of importance is the means for internally applying heat to the oil contained in the retort while held under a self-imposed super-atmospheric vapor pressure for the purpose of bringing about a conversion of such oil.

95 Preferably this feature is electrically operated and embodies an electric heater 30 comprising one or more resistance rods, or resistors of carbon or other suitable material, which are adapted to be maintained at a heat sufficient to crack and convert the oils 105 undergoing treatment while submerged within the oil.

110 By controlling the electric current the electric heater may be maintained at a predetermined temperature as rendered desirable by the conditions of operation.

The electric heater 30, as shown in detail in Figures 6, 7, 8 and 9 is made up of a grid or series of parallel resistance rods arranged in the arc of a circle, and so connected that the current may flow through the same to the best advantage.

115 While the precise manner of connecting the resistance rods may be varied to conform to the voltage of the source of supply, I have illustrated a series connection, which is suitable for ordinary working conditions.

120 The electric energy is supplied to the heater by means of a metallic conductor rod 24 which passes through the cap 21 at the summit of the dome 15, and in order to prevent grounding or short circuit of the current, an insulating bushing and gland 25 of suitable material, such as soapstone or 125

long fibre asbestos composition, will be interposed in a tight fitting relation between the cap and the leading in conductor rod 24.

So also, a leading out conductor rod 26 5 may similarly pass through the bottom of the retort section 13, and the current for operation will be supplied from the mains 27 and 28.

The conductors 24 and 26 project into the 10 heating section 13 and their adjacent ends are spaced apart to form a gap which, if desired, may be bridged or filled in by a suitable insulating or non-conducting interponent 29, as shown in Figs. 6, 8 and 9.

15 While a variety of materials are available from which this insulating interponent may be made, I prefer that it shall be formed of a comparatively hard and unyielding insulating material, such for example as soap-stone or porcelain, so that the interponent 20 may form a rigid connection between the conductors 24 and 26 in order to prevent or obviate any undesirable looseness and lateral movements of the heater and lend stability 25 and strength to the structure.

While this non-conducting interponent 29 may be connected to the spaced terminals 24 and 26 in different ways, that shown in Fig. 9 will be found simple and serviceable. 30 This connection comprises an internally threaded collar 29' in screw-threaded engagement with the end of the adjacent terminal and the corresponding end of the insulating interponent.

35 In my preferred form of grid or electric heater, the current passes into the first resistance rod, say that indicated by 30' (Fig. 9) through a link 31, which is tightly secured to the terminal of the conductor 24 by means of a clamp nut 32. The upper end of the resistance rod 30' is screw threaded to provide an engagement for the complementary clamp nuts 33 and 34. The current thus passes down through the resistance rod 30', then across the link 35 (Fig. 6) up through the adjacent rod 36, across link 37 and down the next resistance rod 38, until finally it passes out through the last link 39 and into the leading out conductor 26, to which the last mentioned link is electrically connected by lock nut 32 in a similar manner to that of the first link 31.

By this arrangement, each of the rods 30', 36 and 38, etc. will carry the same current and, as they are constructed of material having like resistances, they will be evenly and equally heated. By suitable current regulating devices (not shown), these rods may be maintained at any predetermined temperature, even though submerged 60 in the oil.

This internal electric heater or resistor constitutes a feature of considerable importance in my invention by reason of the fact 65 that in operating upon certain classes of

oil it is desirable to localize the application of internal heat, thereby tending to eliminate the evaporation of undue quantities of oil prior to their conversion by the action of the submerged electric heater.

To this end, I have provided a heat-insulating shell 40, as shown in Figs. 2 and 3, which shell provides a relatively restricted center channel or passage for the upward flow of the oil towards the electric heater 70 30. This heat-insulating shell 40 rises above the level of the oil, as indicated in Fig. 2, and preferably has its upper end 41 in interfitting relation with the overlying cylindrical crown or dome 15. Its lower end, 80 however, is either provided with apertures 42 for the inflow of the oil or it may be carried upon a suitable perforated support rising from the bottom of the retort.

With this construction, it will be understood that whenever the oil to be converted is admitted into the retort and brought to the proper level indicated by the gages 14, 16 and 23, it will assume the same level on the outside of the insulating shell 40 as it 85 will on the inside thereof. In this manner the electric heater 30 will be maintained in predetermined submerged relation and the oil lost by evaporation in the overlying dome will be constantly and uniformly replaced by fresh quantities of oil to be converted. The heater, therefore, will always be completely submerged and a constant oil level maintained above it.

In order to insure that the electric heater 100 brings about a local application of a very considerable degree of heat, it is in many cases desirable to prevent the dissipation or spread of heat through a large body of oil, inasmuch as such action would result 105 in undue evaporation or distillation of oil without any appreciable alteration of its character. The insulating shell 40, being preferably constructed of a cellular and laminated heat-insulating material, admirably 110 serves as a barrier to localize the heat where it is especially effective for the purpose intended.

As the operation of the process proceeds, new quantities of original or fresh oil constantly flow into the converter and rise past the heater to compensate for that removed in the form of evolved vapors and fixed gases. By means of the glass sight gage on the converter and gages column, the surface level 120 of the oil may be under constant observation and may thus be held at a predetermined height. With the electric heater 30 in operation, oil will be constantly flowing toward and into intimate contact with the 125 highly heated resistor, thereby becoming cracked and changed into lighter or more volatile products.

It will be understood that during the operation, the raw or unconverted oils will 130

4
be relieved of more or less of the carbon of which they are in part composed. This of course alters their chemical character and converts them from one or more of the products of the hydrocarbon series into others of an essentially different character. The carbon which is removed in this manner will be in part deposited on the highly heated resistor and in part precipitated in the adjacent oil, being to some extent held in suspension and to some extent gravitated through the oil toward the bottom of the converter. The heavy residual oil, containing this gravitated carbon, may be withdrawn as desired through the pipe 17 and valve 18.

Inasmuch as the precise degree of temperature at which the electric heater should be maintained in practice largely depends upon and varies with particular conditions, such as the composition of the raw oil to be converted, I may state that the temperature will in practice ordinarily vary so that the resistor will have a high black temperature or an incandescence from a low cherry red to a white heat, according to the oil being treated.

When operating in this manner, it has been observed that apparently only a part of the oil comes in direct contact with the resistor for the reason that the conduction of heat is sufficient to evaporate a certain portion at a lower temperature than is requisite for the cracking operation. Accordingly, the vapors passing into the dome will be composed not only of the oil which has been converted by the breaking up of its molecules during its exposure to the high heat, but also will contain a certain proportion of the volatilized and uncracked original oil.

The mixed vapors of the original and the cracked oil are evolved very rapidly, owing to the intense heat of the resistor and consequently care should be exercised to keep the oil level at the proper height and not permit it to fall below or approach the top of the electric heater, for the resistors would protrude above the level of the oil and uneven heat would result, the upper or exposed part of the resistors becoming hottest where there is the greatest resistance to the radiation of heat.

The mixed vapors pass from the dome or crown cylinder 15 into a vapor discharge pipe 43, and thence through pipe 44, into a suitable condenser E, of which cooling coils 45 are contained within a tank 47 and mounted on a suitable support 46, if desired.

Since some of the vaporized original oil may tend to condense before reaching the condensing apparatus E, I prefer to connect the vapor discharge pipe 43 with the bottom of the retort 13 by means of the gage column 22 and in this manner utilize the

gage column to enable the preliminarily condensed unconverted oil to be readily passed through the retort again for further treatment.

I also prefer to provide a safety pop valve 47 mounted above the condenser E and in an elbow of the pipe 44, so as to relieve any sudden or excessive pressure above the predetermined vapor pressure at which the process is operating. I may also place in the vapor line 43-44, a thermometer or pyrometer 48 so that the temperature of the converted vapors passing over to the condenser may be observed.

After passing through the coil condensing apparatus E, the oil passes through pipe 50 into a tank 49 of a reservoir F. The upper part of this reservoir is provided with a gas vent pipe 51 controlled by a needle valve 52, and the lower part is provided with a liquid draw-off pipe 53, controlled by valve 54.

A sight gage 55 is located on the tank 49 so that the surface level of the oil may be noted and a pressure gage 56 is provided at the upper part of the tank so that the vapor pressures within the system can be under constant observation in order to make it possible for the operator to be informed when to lower the built up pressure by opening the needle valve 52 of pipe 51. A draw-off tap 57 is at the foot of the condenser E for the purpose of taking samples of distillate from time to time during the operation of the process.

The use of the gas vent pipe 51 and valve 52, in conjunction with the other features of my invention is of great importance, for thereby I am enabled to regulate the predetermined vapor pressure in the apparatus and promote uniformity and certainty in the operation of the entire system from the source of supply through to the end of or beyond the condenser.

As a means of regulating the temperature of the condenser coil 45 of the condenser E, I have provided a cold water inlet pipe 58 and an overflow pipe 59 for the discharge of the heated water which accumulates at the top of the condenser tank, and as a means of observing the pressure in the supply tank 1, I have provided a pressure gage 60 at the top thereof. A pressure gage 61 is also employed at the top of the crown or drum 15 so that the pressure in the converter may be known, as well as at the discharge end in the tank F. When the apparatus is working under satisfactory conditions, both gages 56 and 61 should register the same uniform pressure throughout the system from the valve 10 in pipe 9, through the condenser and in the collecting apparatus F.

The above specifically described apparatus was employed by me in connection with the conversion of light oils, as kerosene, into

napthas and gasolenes at high or cracking temperatures while the oil undergoing treatment and the vapors being condensed were held at superatmospheric pressure,

- 5 Another and more commercially practical apparatus is shown in Fig. 4. This system comprises the various co-related parts shown and described with respect to Fig. 1, but in place of the use of compressed air maintained over the surface of the oil in supply tank 1, a pump 62 is provided to withdraw oil therefrom and force it into a converter C through a preheater B against a back vapor pressure maintained in the preheater B, converter C and running tank F. Inasmuch as it is desired to conserve heat energy in this apparatus, the comparatively cold oil flowing through the pipe 9 is preferably caused to pass through the oil preheater B and thus be raised in temperature before passing into the oil converting receptacle. This preheater may be of any suitable type but preferably embodies a continuously rising coil 63 connected with the outlet pipe 64 which is located at the top so that any air bubbles may readily escape and not form air locks therein. The source of heat for said preheater may be the oil returning from the converter and hot oil receivers at the opposite end of the apparatus, or it may consist of any other suitable heat supplying means.

The converter in this type of apparatus comprises retort 13, an over-lying dome 15 and an under-lying chamber 65 for receiving the heavy bottoms, carbon and other residues, such chamber being provided with a detachable plate 19. The residuum may be drawn off through pipe 17 and valve 18. The means for admitting oil to the converting receptacle is shown as pipe 66 controlled by valve 67, and pipe 68 controlled by valve 69, and by this means oil may be delivered into the upper or lower part of the converter as desired. This converting receptacle is conveniently supported by suitable legs or supports 70 and, like the converter of Fig. 1, preferably comprises a number of sections bolted together to form fluid-tight connections. The heavy bottoms chamber 65 is formed by a pipe-like section having a bottom plate 19 provided with an insulated bushing 71 tightly fitted in central aperture therein. This bushing like bushing 25 at the upper end of the retort, tightly encircles the conductor rod 26 and insulates the same from the metal of the receptacle.

A suitable thermometer or pyrometer 72 may be arranged in permanent relation with the retort 13 and another one 73 with dome 15 so that the temperature of the oil contained therein may be kept under constant observation.

As has been stated the branch line feed pipes 66 and 68 may enter the converter as shown at the top and bottom, and also a branch line pipe 74 having a valve 75 may connect such converter with a return pipe 76 to enable a flow to take place as will be hereinafter described.

The vapor dome 15 comprises a drum like section having one inlet at 66 for the oil coming from the supply tank 1 to the coil 63 of the preheater B and pipe 64, and an outlet pipe 77 controlled by valve 78 for overflow unconverted hot oil.

Since the process of conversion depends on subjecting oil or oily vapors to very high temperatures considerably above their vaporization points, and since this evidently cannot be done without volatilizing in unconverted form large quantities of such oil, it will be necessary to maintain high self-generated vapor pressures within the system and to re-treat such fractions as have escaped cracking by the heat of the submerged heater 30.

By arranging the electric heater in the manner described it is possible to materially reduce the escape of unconverted oils, but it has been found that considerable quantities pass through the receptacle without having been affected. Such oils, being comparatively heavy, may be readily condensed or caught by properly arranged baffle plates, and to this end this invention proposes a structure or system of parts intervening between the converter and condenser for the converted fractions and the unconverted oils which are to be collected and returned for retreatment.

In the embodiment shown in Fig. 4, a vapor trap 79 having a baffle plate 80 intercepts the vapors escaping from the upper part of dome 15 and any heavy parts, not light enough to go through and out through pipe 44, are led back into the converter through pipe 76.

The oily vapors and particles of heavy oil from the converter pass out through pipe 43 and are projected against the plate 80 and this action, as in the steam trap, collects the heavy particles, condenses and throws them down in liquid form. Such vapors as have escaped condensation in the trap 79 pass through pipe 44 to a suitable condenser E, capable of condensing all products which may have a liquid form at ordinary temperatures.

The pop release valve 47 is provided in this form of apparatus and is located over the condenser E in the pipe 44 to insure safety in case the pressure should exceed a pre-determined number of pounds to the square inch, under which the apparatus is working normally.

This apparatus may be operated with the

oil flow either upwardly or downwardly past the electric heater as desired. Thus, when operating with a downward flow of oil, valve 69 in pipe 68 is closed, as well as valve 78 in pipe 77. The incoming oil will then flow through pipe 66 and valve 67 into the dome 15 and passing down through the retort 13 past the electric heater, is led out through pipe 74 and valve 75 and then rises through pipe 76 and from thence into tank 82 through pipe 81.

The hot oil overflow tank 82 is provided with a glass sight gage 83 so that the height of the oil therein may be known in order to indicate when the valve 85 in pipe 84 should be opened to draw off the hot oil into the collecting apparatus D, of which tank 86 is provided with glass sight gages 87. The oil may be withdrawn from this collecting apparatus D by means of pipe 88 and pump 89, which latter will force oil through pipe 90 past check valve 91 and into supply tank 1 for retreatment with new oil. The converted vapors will pass through the trap 79 and other parts as described, the distillates and gases being caught in the running tank F located beyond the condenser.

In case it is desired to have the flow upwardly past the electric heater, valve 67 in pipe 66 and valve 75 in pipe 74 will be closed, while the valve 69 in pipe 68 and valve 78 in pipe 77 will be opened. In this manner oil flowing through pipe 68 and upwardly through retort 13, will overflow through pipe 77 into tank 82 from which it is drawn into collecting apparatus D and returned to supply tank 1 by means of pump 89, as described. The vapors passing off through pipe 43, trap 79 and condensing coils 45 are reduced to distillates and collected as set forth.

In Fig. 5 is illustrated another modified form of converter of very simple structure which differs somewhat from those already described. This type of converter is not provided with a heavy bottoms or residue chamber, and the electric heater 30 is located in the lower part of the retort 13 and is positioned opposite a sight glass 102, adjacent the lower end of the converter. The lower inlet pipe 68 is disposed adjacent and directly opposite the electric heater so that the incoming oil is projected into contact with the heater. An outlet 77 is provided in the dome 15 so as to carry off any overflowing oil above a predetermined oil level. The electric heater is similar in construction, mounting and operation to the heaters already described in detail.

The converters shown in all of the figures are in free communication with the condensers and running trap tanks for the accumulation of distillates and fixed gases, and the super-atmospheric vapor pressures generated in the converters extend to and

through the condensers and the running trap tanks located beyond the condensers.

Having described my invention, what I claim as new and desire to secure by Letters Patent is:

1. The process of converting hydrocarbon oils that comprises subjecting oil to direct contact with an electric resistor, immersed therein and heated electrically to a cracking temperature, and maintaining a super-atmospheric pressure upon the oil under treatment.

2. The process of cracking hydrocarbon oils that comprises subjecting the oil to direct contact with a carbon resistor immersed in the oil and heated electrically to a cracking temperature, while maintaining the oil under super-atmospheric self-imposed vapor pressure, and condensing the evolved vapors.

3. The process of converting hydrocarbon oils that comprises subjecting the oil to direct contact with an electric resistor immersed therein and heated to a cracking temperature by the passage of an electric current, maintaining a regulated super-atmospheric pressure upon said oil, and condensing the evolved vapors under substantially the same super-atmospheric pressure.

4. The process of converting liquid hydrocarbon oils that comprises maintaining a carbon resistor immersed in the oil at a cracking temperature by the passage of an electric current, while maintaining a regulated super-atmospheric self-imposed vapor pressure, and condensing the evolved vapors under substantially the same super-atmospheric self-imposed vapor pressure.

5. The process of converting hydrocarbon oils that comprises subjecting the oil in a confined receptacle of restricted cross-section to a cracking temperature developed by an electric resistor immersed in the oil and heated electrically by the passage of an electric current, while maintaining upon the oil sufficient superatmospheric vapor pressure to hold it in liquid form during the conversion process, removing the evolved vapors from the cracking zone, and effecting a condensation thereof while maintaining substantially the same superatmospheric vapor pressure thereon.

6. The process of converting hydrocarbon oils that comprises subjecting the oil locally to a cracking temperature developed by an electrically heated resistor immersed in the oil, while maintaining superatmospheric self-imposed vapor pressure upon the oil during conversion, removing the evolved vapors, condensing the heavier constituents thereof and returning them to the action of the electric resistor for further treatment, removing and condensing the lighter constituents of the evolved vapors, and maintaining substantially the same self-imposed

vapor pressure throughout the entire operation.

7. The process of converting hydrocarbon oils that comprises flowing a stream of liquid oil through a restricted passage and past an electrically heated resistor disposed therein and immersed in the oil whereby said oil is raised in transit to a cracking temperature by the local application of cracking heat thereto, and maintaining a regulated superatmospheric self-imposed vapor pressure upon the oil during the conversion process.

8. The process of converting hydrocarbon oils that comprises flowing a stream of liquid oil through a restricted passage containing an electrically heated resistor maintained at a cracking temperature, and thence into an enlarged chamber where the evolution of vapors takes place, removing the evolved vapors, selectively separating the heavier from the lighter constituents thereof, returning the heavier constituents in cy-

clic passage through the cracking zone, condensing and collecting the lighter constituents, and maintaining a superatmospheric self-imposed vapor pressure upon the oil throughout the entire process.

9. The process of converting liquid hydrocarbon oils that comprises continuously flowing a stream of liquid oil in a single passage through a cracking zone of restricted cross-section and past an electrically heated resistor disposed therein whereby the oil in transit is locally cracked in contact with said resistor, delivering the oil into an enlarged chamber where vaporization takes place, separately removing evolved vapors and liquid oil from said chamber, and maintaining superatmospheric vapor pressure upon the oil throughout its treatment.

In witness whereof I have hereunto set my hand and seal this 9th day of October, 1922.

JOSEPH H. ADAMS.
